CONDENSING APPARATUS.

1,405,821.

Specification of Letters Patent. Patented Feb. 7, 1922.

Application filed November 8, 1918. Serial No. 261,708.

To all whom it may concern:

Be it known that I, RAYMOND N. EHRHART, a citizen of the United States, and a resident of Edgewood, in the county of Allegheny and State of Pennsylvania, have made a new and useful Invention in Condensing Apparatus, of which the following is a specification.

This invention relates to condensing apparatus and particularly to air extracting apparatus for condensers.

Condensers employed for condensing steam exhausted from power developing units are usually provided with means for extracting non-condensable fluids, such as air from the condenser. The degree of vacuum obtainable within a condenser is in a large measure dependent upon the air (that is, non-condensable fluid) content of the fluids within the condenser. If no air were present within the condenser the vacuum would absolutely correspond to the temperature of the condensate, or in other words, the pressure within the condenser would correspond to the theoretical vaporizing pressure of the condensate at the temperature of the condensate within the condenser. A slight amount of air within the condenser materially varies the pressure conditions, with relation to condensate temperatures, and consequently reduces the efficiency of the condenser. For this reason it is essential to so design the air extracting apparatus that it will be capable of extracting all the air entering the condenser under substantially normal operating conditions. In this connection attention is called to the fact that the word air is herein employed to include all vapors or fluid which may enter the condenser and which are not capable of being condensed under conditions obtaining within the condenser. Where the air extracting apparatus is designed for maximum extracting conditions and operates continuously under full capacity conditions, there is some loss occasioned by the fact that the power consumption of the air extracting apparatus is not commensurate with variations in the amount of air to be withdrawn. Steam actuated air ejectors are sometimes employed as the air extracting apparatus for condensers, primarily because they are simple in construction and operation. It is a characteristic of such ejectors that they are efficient only

when operating under the load conditions for which they are designed. When the load is light, that is, when there is only a small quantity of air to be ejected, substantially the same quantity of motive steam must be supplied to the ejector as when the ejector is working at full load capacity, in order to prevent "upsetting" of the ejector, that is, in order to prevent momentary back flows or momentary equalizations of pressure between the inlet and exhaust of the ejector.

In my co-pending application for patent, entitled "Ejector apparatus," filed August 21, 1918, Serial No. 250,899, I have disclosed a plurality of ejectors connected in parallel with the condenser and so arranged that motive fluid may be supplied to one or more of the ejectors in response to the operation of a controlling device which is responsive to the quantity of air to be extracted from the condenser. With such an arrangement, each ejector can be of proportionately smaller capacity according to the number installed, so that when they are all in operation their combined capacity is ample to efficiently withdraw the maximum amount of air encountered under normal operating conditions. Therefore if the amount of air to be extracted is small, one ejector operating at maximum capacity and consequently with high efficiency is in operation, and the others are successively brought into operation as the quantity of air to be removed increases. For this reason the steam consumed in their operation is proportional to the work done, while in the case of a single ejector, a sufficient quantity of steam to carry the full load, is used under light as well as full load conditions and consequently steam is wasted when the ejector is not operating under full load conditions.

In the apparatus herein illustrated, a plurality of the ejectors, similar to those disclosed in the above noted co-pending application are employed, and this invention has for a broad object to produce a condenser apparatus wherein the motive fluid admission to the ejector apparatus is controlled by mechanism responsive to variations in the quantity of non-condensable fluid within the condenser.

Another object of the invention is to produce means for controlling the admission of motive fluid to the ejector apparatus in response to relative variations in temperature

between the steam entering and the condensate leaving the condenser.

Another object is to produce thermostatic means for controlling the motive fluid adjustment to the ejector apparatus responsive to relative variations in temperature between the fluid entering the condenser and the condensate leaving the condenser which may be adjusted to compensate for the differences in operating conditions occasioned by external changes of temperature incident to the changes in the seasons.

A serious air leak or insufficient extraction of air by the air extracting apparatus, occasions a relatively greater difference in the temperature of the incoming steam and the condensate collected within and delivered by the condenser than is the case where the air content of the fluids within the condenser is normally low. The condensate temperature will be less than the theoretical temperature corresponding to the pressure within the condenser, and considerably less than the temperature of the incoming steam. Where other conditions are maintained constant the difference in temperatures between the incoming steam and the outgoing condensate should also remain constant for each individual condenser and a variation in this determined temperature difference will indicate air leakage or insufficient air pump capacity. My present invention therefore contemplates controlling the ejector apparatus in response to variations in this temperature difference so as to maintain the air content of the fluids within the condenser as low as possible with the least expenditure of motive steam for the air extracting apparatus.

It will of course be apparent that variations in other conditions, for example, condensing water temperature, will affect the operation of the apparatus, and for that reason I have provided adjusting means for adjusting the apparatus to conditions encountered. During the winter months the condensing water is much colder than during the summer months, and as a result the vacuum within the condenser approaches more nearly the absolute vacuum, and air entering a condenser operating under winter conditions will occasion a greater difference between the temperature of the condensate and the incoming steam than the same quantity of air entering the same condenser operating under summer conditions. This wide variation in operating conditions may be compensated for by the adjusting means to which I have referred.

One embodiment of the invention is disclosed in the accompanying drawing, wherein—

The figure is a diagrammatic illustration of condensing apparatus embodying the invention, portions of the apparatus being

shown in section for convenience of illustration.

Referring to the drawing, the apparatus includes a condenser 1, receiving exhaust steam from a power unit, not shown, through a steam inlet 2. The condenser shown is of the surface type and is provided with a nest of cooling tubes 3, through which cooling or condensing water is circulated. The condensate resulting from the condensation of the steam falls to the bottom of the condenser and flows into a hot well 4, from which it is extracted by a centrifugal pump 5 and is discharged through the passage 6, to a feed tank or feed water heater, not shown.

The condenser is provided with an air outlet 7, which communicates with a plurality of jet ejectors, 8, 9 and 10, by means of the conduit 11. The ejectors 8, 9 and 10 are connected in parallel with the conduit or manifold 11 and are adapted to be operated on motive steam supplied to the header 12 from which steam flows to the ejectors 8, 9 and 10 through branch conduits 8', 9' and 10' respectively. These conduits 8', 9' and 10' are respectively provided with controlling valves 8'', 9'' and 10'' which may be preferably of the quick opening and closing type. As shown, valves 8'', 9'' and 10'' are each provided with an operating lever 8^a, 9^a and 10^a respectively, by which the valves may be operated by mechanism to be hereinafter described.

The ejectors 8, 9 and 10 exhaust into a common manifold conduit 13 which communicates preferably with a feed tank or feed water heater, not shown. A check valve 14 is located between the discharge port of each ejector and the manifold 13 and is adapted to close and prevent the passage of fluid from the exhaust manifold 13 back through the ejector passages when the steam supply to the ejector is shut off. As illustrated in the figure, the check valves of the ejectors 9 and 10 are closed and so are the control valves 9'' and 10'', while the valve 8'' is shown open as indicated by the oblique position of the valve lever 8^a. The check valve 14 of the ejector 8 is also shown in the open position where it is being held by the passage of fluid through the exhaust passage of the ejector 8.

It is the purpose of this invention to provide means whereby the valves 8'', 9'' and 10'' controlling the supply of motive fluid to the ejectors 8, 9 and 10 respectively may be opened successively for the purpose of increasing the air extracting capacity of the apparatus. It is also an object to provide a mechanism whereby this operation may be brought about in response to variations in the quantity of air within the condenser and a resulting variation in the relative differences in temperature between the steam

entering and condensate leaving the condenser.

The above results are obtained in the illustrated embodiment of the invention by means of a thermostatic apparatus including a pair of expansion members, 15 and 16, each comprising a metal tube made preferably of brass or some other metal having a high coefficient of expansion. These tubes 10 are anchored solidly in a base block 17, mounted upon any suitable foundation or support and are pivotally connected, at their free ends, to a rocking lever or beam 18. The upper or free end of the beam 18 is 15 pivotally connected at 20, to a valve operating bar 21, which is provided with an adjusting nut 22, whereby the length of the bar 21 may be adjusted to compensate for variations in operating conditions; for example, wide variations in condensing water 20 temperature. The bar 21 is provided with a plurality of pins 23, 24 and 25, one for each valve lever 8^a, 9^a and 10^a respectively, and the length of the bar 21 may be adjusted 25 by means of the adjusting nut so that when the thermostat is in the position it would normally assume when the quantity of air in the condenser is reduced to the practical operating minimum, the pin 23 will be in 30 operative engagement with the valve lever 8^a, so as to hold the valve 8^a in open position as indicated in the drawing.

The thermostat tube 15 is subjected to the heat of the steam entering the condenser. 1. This is accomplished by providing the tubes 35 26 and 27, the former connecting the upper end of the thermostat tube 15 with the interior of the condenser at a point immediately adjacent the inlet thereof, and the latter connecting the lower end of the thermostat tube 15 with the interior of the condenser at some point near the region of complete condensation as, for example, below the baffle wall 28 and above the normal level 40 of the condensate. Under such conditions a circulation of steam will be set up, passing from the condenser inlet 2 through the tube 26, through the thermostat tube 15, and into the interior of the condenser through the 45 passage 27, thus continually subjecting the thermostat tube 15 to the heat of the incoming steam which will cause the length of the thermostat tube 15 to vary in response to variations in the temperature of the 50 incoming steam.

The thermostat tube 16 is subjected to the heat of the condensate leaving the condenser, by causing a portion of the condensate to pass through the tube. As shown the lower 60 end of the tube 16 is connected to the condensate discharge conduit 6, by means of a conduit 29 and the condensate is discharged from the tube through a conduit 30, which may communicate with the feed tank or 65 water heater. Under such conditions the

length of the tube 16 will vary by expansion and contraction in response to the variations in temperature of the condensate leaving the condenser.

As the tube 15 is responsive to variations 70 in the temperature of the steam entering the condenser, and as the tube 16 is responsive to variations in temperature of the condensate in the condenser, it will be evident that any variations in the relative differences in temperature between the two fluids, will result in a movement of the rocking beam 18, due to variations in length of the thermostat tubes.

Assuming that the temperature of the 80 condensate is more or less uniform, its ultimate temperature depending, of course, upon the temperature of the cooling water circulated through the condenser, it will be seen that the rocking beam 18 will be swung 85 clockwise by the thermostat upon an increase in the existing temperature of the steam entering the condenser. Any accumulation of air, due to leakage or insufficient extraction by the pump or ejector 8, causes 90 the pressure within the condenser to rise, thus increasing the temperature of the steam at the inlet to the condenser. Further increase of temperature occasions a further 95 expansion of the tube 15 and moves the valve bar 21 further to the right, and if the conditions warrant it the valves 9^a and 10^a are therefore successively opened and the ejectors 9 and 10 called into operation to assist the ejector 8 as air expelling devices. As 100 soon as the pressure within the condenser drops to normal, the valves 9^a and 10^a close in response to the operation of the thermostatic device.

The complete operation is as follows: 105 Assuming that the parts are in the position indicated in the drawing wherein the valve 8^a is shown as open and the ejector 8 is operating to eject air from the condenser, the valve 8^a is held open by the pin 23, by 110 reason of its engagement with the valve lever 8^a. If the quantity of air entering the condenser 1, during a given period of time, is greater than the ejector 8 is capable of extracting during the same period and assuming that the condenser is capable of condensing all the steam supplied thereto, it will be apparent that the pressure within the condenser 1 will increase proportionally 115 with the accumulation of air, which will in turn cause the temperature of the steam entering the condenser to increase correspondingly. This condition causes the thermostat tube 15 to expand, thereby causing a movement of the valve bar 21 to the right, so as 120 to open the ejector valve 9^a, thus causing the ejector 9 to assist the ejector 8. If the ejectors 8 and 9 are still incapable of extracting all the air entering the condenser 125 the pressure will continue to rise in the con- 130

denser and the temperature of the incoming steam will rise correspondingly, occasioning further expansion of the thermostat tube 15, and thereby causing the valve bar 21 to move to the right until it opens the valve 10", controlling the delivery of motive fluid to the ejector 10.

As the air content is reduced the pressure in the condenser 1 falls, resulting in a contraction of the thermostat tube 15, which action draws the valve bar 21 to the left, permitting the valves 10" and 9" to be closed successively in the order named. As will be apparent, the length of the bar 21 may be adjusted to meet the varying conditions encountered in the operation of the device when operating in summer or winter, or to suit the characteristics of the individual condenser. It will be apparent that normal variations in both the temperature of the incoming steam and the outgoing condensate will cause both the tubes 15 and 16 to expand or contract corresponding amounts and will therefore not vary the operation of the ejectors.

While I have described and illustrated but one embodiment of my invention, it will be apparent to those skilled in the art that various changes, modifications, additions and omissions may be made in the apparatus described and illustrated without departing from the spirit or scope of the invention, as set forth by the appended claims.

What I claim is:

35 1. In combination with air extracting apparatus for extracting noncondensable fluid from a condenser, a motive fluid supply therefor, and controlling means for the motive fluid supply responsive to relative variations in temperature between the fluids entering the condenser and the condensate within the condenser.

2. In combination with a plurality of air extracting devices for extracting non-condensable fluid from a condenser, a motive fluid supply for said devices and controlling means for the motive fluid supply responsive to relative variations in temperature between the fluid entering the condenser and the condensate formed therein.

3. In combination with a plurality of fluid operated air extracting devices for extracting non-condensable fluids from a condenser, means for controlling the delivery of motive fluid to each device, and means responsive to relative variations in temperature between the fluid entering the condenser and the condensate leaving the condenser for successively actuating said first mentioned means.

4. In combination with ejector apparatus for extracting non-condensable fluid from a condenser, a means responsive to relative variations in temperature of the fluid entering the condenser and the condensate

therein, for increasing the motive fluid admission to the ejector apparatus as said difference in temperature increases.

5. In combination with ejector apparatus for extracting fluid from a condenser, a means responsive to relative variations in temperature of fluid entering the condenser and the condensate therein, for decreasing the motive fluid admission to the ejector apparatus as said difference in temperature decreases.

6. Condensing apparatus comprising in combination a condenser receiving steam to be condensed, fluid actuated means for ejecting non-condensable fluids from the condenser and thermostatic means for controlling the motive fluid admission to the ejecting means responsive to relative variations in difference in temperature between the steam entering the condenser and the condensate withdrawn therefrom.

7. Condensing apparatus comprising in combination a condenser, fluid actuated means for ejecting non-condensable fluids from the condenser, means for controlling the motive fluid admission to said ejecting means, and a pair of expansion members for operating the controlling means adapted to actuate the controlling means when their relative temperatures vary, one of said expansion members being subject to the heat of the fluid to be condensed entering the condenser, and the other being subject to the heat of the condensate precipitated within the condenser.

8. Condensing apparatus comprising in combination a condenser receiving steam, means within the condenser for condensing the steam, fluid actuated means for ejecting the non-condensable fluids from the condenser, means for controlling the motive fluid admission to the ejecting means, and a pair of expansion members adjustably connected to the controlling means and adapted to actuate the controlling means when their relative temperatures vary, and subject respectively to the temperature of the steam entering the condenser and the condensate therein.

9. Condensing apparatus comprising in combination a condenser receiving steam, means within the condenser for condensing the steam, fluid actuated means for ejecting non-condensable fluids from the condenser, means for controlling the admission of motive fluid to the ejecting means, and a pair of hollow expansion members for operating the controlling means when their relative temperatures vary, one of said members receiving steam from the condenser and being subject to the heat thereof, and the other receiving condensate from the condenser and being subject to the heat thereof.

10. Condensing apparatus comprising in combination a condenser receiving steam,

- means within the condenser for condensing the steam, fluid actuated means for ejecting non-condensable fluids from the condenser, means for controlling the admission of motive fluid to the ejecting means, and a pair of hollow expansion members for operating the controlling means when their relative temperatures vary, through one of which steam from the condenser is circulated, and 10 through the other of which condensate from the condenser is circulated, and each being subject to the heat of the fluid passing therethrough.
11. The combination with ejector apparatus for extracting noncondensable fluids from a steam condenser, of a motive fluid supply therefor, and controlling means for the motive fluid supply including means responsive to variations in the temperature of 20 the gaseous fluid entering the condenser.
12. In combination with a condenser, a plurality of air ejecting devices for withdrawing non-condensable fluids from the condenser, and thermostatic means responsive to variations in the relative temperatures 25 of the steam entering and the condensate withdrawn from the condenser for controlling the operation of said devices.
13. In combination with a condenser, a plurality of air ejecting devices for withdrawing non-condensable fluids from the condenser, means for rendering one or more of said devices operative or inoperative, and means responsive to variations in the relative difference in the temperature of the steam 30 entering and the condensate leaving the condenser for controlling the operation of said first mentioned means.

In testimony whereof, I have hereunto subscribed my name this 5th day of November, 40 1918.

RAYMOND N. EHRHART.
